TIME STAMP

Burdette H. Phillips, Endicott, N. Y., assignor, by
mesne assignments, to International Business
Machines Corporation, New York, N. Y., a cor-
poration of New York

Application September 25, 1931
Serial No. 565,093

7 Claims. (Cl. 197—175)

This invention relates to feeding mechanism for inking ribbons like those used in printing devices such as time stamps and time recorders.

The primary object of the invention is to provide an inking ribbon feeding mechanism in which the direction of the ribbon feed is reversed automatically after a predetermined number of impressions have been made by the printing devices.

10 A further object is to provide an inking ribbon feeding mechanism which is simple in its construction, has few working parts, and is positive in its action.

Another object is to provide a ribbon feeding mechanism which reverses the direction of feed without the use of complicated mechanism such as devices controlled by the tension of the ribbon or by tripping devices fixed to or controlled by the ribbon itself.

20 A more specific object is to provide novel means for joining the ends of the ribbon to the ribbon spools which means also serves to connect the ribbon spools to the drive shafts therefor in a manner to permit the mechanism to yield or slip without damage to the latter in case the ribbon should become bound or stuck as by becoming completely unwound from one of the spools before the reversing mechanism takes effect.

25 A further object is to provide a ribbon feeding mechanism so arranged that the ribbon may be easily removed and replaced without difficulty and without requiring readjustment of the mechanism after the ribbon has been replaced.

30 Various objects, advantages, or features of the invention will be more fully pointed out in the following description and claims, or will be apparent after a study thereof and of the accompanying drawings.

In the drawings:

40 Fig. 1 is an elevation of the left side of a time stamp embodying the present invention, the cabinet enclosing the time stamp being shown in section.

45 Fig. 2 is a vertical section through the ribbon feeding mechanism and is taken substantially on the line 2—2 in Fig. 1.

Fig. 3 is a plan view of the ribbon reversing mechanism.

50 Fig. 4 is a vertical section taken substantially on the line 4—4 in Fig. 2.

Fig. 5 is a vertical section taken on the line 5—5 in Fig. 2.

55 Fig. 6 is a detail view illustrating the manner in which the ribbon is attached to the ribbon spool.

The problem of constructing ribbon feeding

mechanisms for time stamps is a difficult one owing to the fact that very little space is available for the various mechanisms. It is necessary, in order to reduce the size and weight of the time stamp, to make the various mechanisms as compact and simple as possible, yet they must be both positive and reliable in their action and capable of being used for long periods of time without skilled attention. The amount of space available in which to place the feeding mechanism for the inking ribbon is usually very small, consequently it is necessary that said mechanism be very compact and as simple as possible.

Ribbon feeding mechanisms hitherto provided in time stamps have, for the most part, been controlled by the tension of the ribbon since limitations of space prevent the use of devices fixed to the ribbon for controlling the reversing mechanisms. In some cases the ribbon feed has been reversed by hand. In other cases endless ribbons have been used. The type of ribbon feeding mechanisms controlled by the tension of the ribbon has not proven entirely satisfactory owing to a tendency to stick and fail to work at times and also because there is a point at each end of the ribbon where the ink quickly becomes exhausted due to a tendency to take several impressions from the same part of the ribbon before sufficient tension has been secured in the ribbon to operate the tension device. This means occasional poor impressions from the type wheels and is very annoying. The endless type of ribbon is not satisfactory because it usually has a bulky seam causing poor impressions at times and is difficult to replace quickly and easily.

The present invention aims to provide a ribbon feeding mechanism which reverses the direction of feed practically instantly and before any dry spots can develop at either end of the ribbon due to repeated impressions through the same part of the ribbon. This result is obtained, as will now be explained, by reversing the feed without the use of tension devices and by mechanism effective after a predetermined number of impressions.

The drawings illustrate the invention as embodied in a time stamp similar to the one shown and described in Letters Patent No. 1,798,583, granted March 31, 1931, however, it is desired to point out that the invention may be embodied in other time stamps as well. Indeed, the invention may be embodied in printing machines other than time stamps and it is not desired to limit the scope of the invention either to the specific

60

90

95

100

105

110

time stamp selected to illustrate the invention or to time stamps in general.

The various mechanisms of the time stamp are fully illustrated and described in the patent referred to herein, consequently only such parts thereof as may be involved in the present invention will be described in detail.

The time stamp is provided with a base 10 on which rests a base frame 11 supporting near one end thereof side frames 12 of which there are two mounted in spaced relation on the frame 11 and arranged to overhang a considerable part of the top surface of base frame 11 so as to provide an opening 13 permitting insertion of the record or paper to be stamped. The base frame 11 supports the platen operating solenoid 14, the contacts 15 controlling energization of said solenoid to effect printing, and the mechanism for operating contacts 15 including the switch bar 16. The frames 12 support the type wheels for printing the time and dating wheels (not shown), the ribbon feeding mechanism, and the secondary clock movement 17. The cabinet or housing for the time stamp is made in two parts, the lower half enclosing the base frame 11 while the upper half encloses the frames 12 and mechanism carried thereby.

The platen 18 is fixed to the upper end of a vertically slidable plunger 19 guided by a fixed core 20 and is secured to a movable plunger 21 cooperating with the fixed core 20. The fixed core 20 is secured to a member 22 shaped like an inverted "U" and fixed to the underside of the frame 11 adjacent the opening in said frame in which the platen 18 moves. The arms of the member 22 extend downwardly on each side of the coil of the solenoid 14 and cooperate with a plate 23 secured to the movable plunger 21. The member 22 forms part of the magnetic circuit and tends to concentrate the magnetic lines of force upon the ends of plate 23 thereby augmenting the force applied to the platen 18 by the plunger 21. The plate 23 has a lug 24 cooperating with a notch 25 in one arm of a bell crank 26 pivoted at 27 to the base 11.

Whenever the switch bar 16 is pressed inwardly or to the left as in Fig. 1, the contacts 15 will close thereby energizing solenoid 14 and causing the plunger 21 to be drawn upwardly to effect an impression from the type wheels by platen 18. At the same time the plate 23 will be drawn upwardly and, due to lug 24 and notch 25, the bell crank 26 will be rocked counterclockwise (Fig. 1). This movement of bell crank 26 is utilized to operate the feeding mechanism for the inking ribbon which will presently be described.

All the mechanisms so far described or mentioned, except the ribbon feeding mechanism, are fully illustrated and described in Patent No. 1,798,583 and for a more detailed understanding thereof reference may be made to said patent. The feeding mechanism for the inking ribbon is mounted upon a plate 28 secured to the left side frame 12 (Figs. 1 and 2).

The inking ribbon 29 (Fig. 1) is secured at both ends to sleeves 30 driven by shafts 31 to which are secured driving pinions 32 adapted to be driven in a fashion to wind the ribbon 29 thereon in a manner presently to be described. The inking ribbon 29 passes from the lower sleeve (or "spool" as it will be termed hereinafter) over guide rollers journaled in the side frames 12 at 33, over a similar guide roller journaled at 34 in frames 12 and thence is wound on the upper spool 30. The portion of the ribbon extending between

the rollers journaled at 33 overlies the platen 18 and is between the latter and the type wheels (not shown).

The manner in which the ribbon is secured to the spools 30 constitutes a novel feature of the invention and will now be explained in detail by reference to Figures 2, 5 and 6, which show the construction of the upper right hand spool (Fig. 1). Since both ribbon spools are alike a description of one will be sufficient to explain the construction of the other. The end of the ribbon has a loop formed therein by a seam 35 and the spool 30 is slipped into said loop. The spool 30 and the loop in the ribbon 29 both have coating cut-away portions 36, 37, respectively, so that in effect two loops are formed in the end of the ribbon, both said loops extending around the spool 30 at each end of the cut-away portion 36. The ribbon is fastened to the spool 30 by means of a spring clip 38 formed of a piece of sheet metal shaped like a flattened "H", the vertical bars of the "H" being bent as at 39 to form lugs partly encircling the ends of the spool 30 while the cross bar of the "H" is flat and bent toward the axis of the spool as at 40 so as to project inwardly through the cut-out portions 36, 37, in the spool 30 and ribbon 29 as shown in Figures 5 and 6.

It will be observed that shaft 31 is provided with a flat portion 41 against which the flat bent portion 40 presses so that ordinarily the shaft 31, 105 spool 30, and spring clip 38 move as one in winding or unwinding the inking ribbon 29.

If, for any of several reasons, the ribbon 29 should become stuck or bound as when the ribbon has been completely unwound from one spool, 110 the shaft 31 driving the other spool will merely turn idly without further winding the ribbon thereon owing to the flat portion 40 of the spring clip 38 associated with said last named spool slipping out of the flat portion of the shaft 31 115 driving said spool. Thus no damage to the ribbon feeding mechanism can result when the ribbon becomes bound or stuck since the flat bent portion 40 will merely alternately slip out of and back into contact with the flat portion 41 in the 120 shaft 31 driving the spool 30 which is winding the ribbon as said shaft turns.

The shafts 31 are provided with spool flanges 42 securely held against the hubs of gear pinions 32 by a nut in the end of the shaft 31, a portion 125 of the hub of said pinion being turned down to a smaller diameter than the rest of the hub as at 43 and journaled in the left frame 12. The ends of the shafts 31, opposite pinions 32 are turned to a smaller diameter and journaled in 130 supporting brackets 44 removably secured to the right frame 12 to permit removal of the spool 30 when the ribbon is to be replaced. The bracket 44 is fully described in Patent No. 1,798,583 and has a spool flange 45 fixed thereto for compell- 135 ing the ribbon to wind evenly on the spool 30.

The operation of replacing the inking ribbon when worn out is a simple one. The brackets 44 are removed, the sleeves or spools 30 slipped off the shafts 31, and the clips 38 removed. The 140 spools 30 may then be slipped out of the loops in the ends of the old ribbon and one of them inserted in the loop formed in the loose end of the new ribbon and thereafter the clip 38 replaced by pressing the spool 30 between the prongs 39, 145 taking care of course to see that the cut-away portions 36, 37, in the sleeve 30 and ribbon 29 are opposite each other. The ribbon spools 30 may then be slipped back on the shafts 31 and the brackets 44 replaced.

The mechanism for feeding the inking ribbon and reversing the direction of feed when the end of the ribbon is reached comprises mechanism mounted on the plate 28 secured to the left side of frame 12. Journalled in a stud 46 carried by the plate 28 is a gear 47 meshing with two pinions 48 loosely mounted in the ends of a rock lever 49 also loosely mounted on stud 46. When the rock lever 49 is in the position shown in Fig. 1 the right-hand pinion 48 meshes with and turns the adjacent gear 32, thereby driving the upper right-hand ribbon spool 30 in a direction to wind the ribbon thereon. On the other hand, when the lever 49 is rocked counterclockwise (Fig. 1) such movement will bring the left-hand pinion 48 into mesh with the lower left-hand pinion 32 so as to drive the latter in a direction to wind the ribbon on the lower left-hand spool. It will be seen, therefore, that the direction in which the ribbon is fed depends on the position of the rock lever 49.

The gear 47 is turned an increment each time the solenoid 14 is operated to effect an impression from the type wheels by means of a rock lever 50 loosely journaled on the stud 46 and carrying a spring-urged pawl 51 pivoted thereto which engages the teeth of a ratchet wheel 52 secured to the right side of the gear wheel 47. One end of a link 53 has a pin and slot connection at 54 to an arm of bell crank 26 while the other end is pivoted to a stud in rock lever 50 carrying the pawl 51, the spring 55 actuating said pawl being anchored to the right end of the link 53 adjacent the pawl 51 (Fig. 4). Normally the rock lever 50 is held in the position shown in Figs. 1 and 4 of the drawings by means of a spring 56 so that the nose of pawl 51 abuts a stop which has a tendency to force the nose of the pawl 51 into the interdental spaces in ratchet 52 to prevent movement of the latter.

When the solenoid 14 is energized the bell crank 26 will first be rocked counterclockwise by the solenoid 14 to take up the slack in the pin and slot connection 54 and thereafter will draw the link 53 to the left a distance sufficient to rock the lever 50 clockwise just far enough to withdraw the nose of pawl 51 from the tooth in ratchet 52 previously engaged by said pawl and cause the latter to drop into engagement with the next adjacent tooth in the ratchet. As soon as the solenoid 14 is deenergized the bell crank 26 will rock clockwise to its former position, and at the same time spring 56 will rock the lever 50 counterclockwise back to its former position thereby feeding the ratchet 52 one tooth distance in a counterclockwise direction (Figs. 1 and 4).

As a consequence, the gear 47 fixed to said ratchet will be likewise fed in the same direction and through one of the pinions 32, will turn the associated shaft 31 thereby driving one of the ribbon spools 30 a distance sufficient to feed a fresh portion of the ribbon 29 to the printing zone.

The rock lever 49 is adapted to be rocked automatically after a predetermined number of imprints have been made through the medium of a member 57 pivoted at 58 to the plate 28 supporting the ribbon feeding mechanism. The member 57 has a horizontally extending arm having a slotted connection to the stud 48a on which is pivotally mounted the right-hand gear 48 and also has a downwardly extending arm having a nose 59 cooperating with a cam 60 loosely mounted on the stud 46. The cam 60 is integral with a second ratchet wheel 61 also loosely mounted on the stud adjacent the ratchet wheel 52, the

ratchet wheel 61 having a slightly smaller outside diameter than the root diameter of the ratchet wheel 52. The pawl 51 is so constructed that its nose is adapted to engage the teeth of both ratchets 52, 61, but normally cannot drop far enough to engage the teeth in ratchet 61 owing to the fact that the root diameter of ratchet 52 is greater than the outside diameter of ratchet 61, consequently only ratchet 52 will be moved step-by-step under the influence of solenoid 14. It will be observed from Fig. 4 that diametrically opposite pairs of teeth in the ratchet wheel 52 are each provided with a much deeper interdental space 62 or "deep notch", as it will be termed hereinafter, the deep notches 62 having a depth sufficient to permit the nose of pawl 51 to drop far enough to permit said nose to engage a tooth in the ratchet 61 and turn said ratchet one tooth space.

The cam 60 has an abrupt drop 63 and a more gradual rise 64 diametrically opposite thereto so that during one half revolution of the cam the horizontal arm of member 57 will be held up as in Fig. 4 while during the other half revolution said arm will be lowered as in Fig. 1. Owing to the pin and slot connection of the horizontal arm of member 57 to the stud 48a carrying the right-hand pinion 48 the latter will be in mesh with the adjacent gear during one half revolution of cam 60 while during the other half revolution of cam 60 the left-hand pinion 48 will be in mesh with the adjacent gear 32.

The operation of the parts just described will now be given in detail, assuming to begin with that their relation is as indicated in Fig. 4. When the solenoid 14 is energized the bell crank 26 will be rocked thereby taking up the slack in the pin and slot connection 54 and thereafter drawing the link 53 to the left (Fig. 4) causing the pawl 51 to drop into contact with the next adjacent tooth to the one it formerly engaged. The spring 56 will be tensioned during the leftward movement of the link 53 and, when the solenoid 14 is deenergized and the bell crank 26 rocks back to its normal position as shown in Fig. 1, said spring 56 will rock the lever 50 counterclockwise thereby feeding the ratchet 52 one tooth space in a counterclockwise direction. Repeated operation of solenoid 14 will cause the ratchet wheel 52 to be moved around step-by-step in the foregoing fashion until the pawl 51 drops into one of the deep notches 62 in said ratchet whereupon the ratchet wheel 61 will likewise be fed a tooth space thereby advancing the cam 60 in a counterclockwise direction and at the same time turning gear 47 to wind the ribbon on the lower left-hand spool 30 so as to feed the ribbon to the left.

After a predetermined number of impressions have been made by operation of solenoid 14 the cam 60 will have turned far enough in a counterclockwise direction to cause the rise 64 in said cam to engage the nose 59 in the member 57 thereby rocking the latter clockwise and depressing the right-hand end of lever 49 so as to cause the right-hand pinion 48 to mesh with the adjacent gear 32. For the next half revolution of the cam 60 the gear 47 and pinion 48 will drive the upper right-hand ribbon spool associated with the right-hand gear 32 in a counterclockwise direction thereby feeding the ribbon 29 to the left. At the end of this half revolution of the cam 60 the abrupt drop in said cam will cause the member 57 to rock back to its original position under the influence of a spring 65 and,

as a consequence, the left-hand gear pinion 48 will again be thrown into mesh with the adjacent gear 32. During the following half revolution of the cam 60 the left-hand ribbon spool 30 will be 5 again turned in a counterclockwise direction thereby feeding the ribbon 29 to the left (Fig. 1).

It will be seen that the direction of feed of the ribbon is controlled by the cam 60, the right-hand spool being rotated to feed the ribbon 29 to 10 the right during one half revolution of the cam while the left-hand ribbon spool 30 will be turned during the following half revolution to feed the ribbon 29 to the left. By making the ribbon slightly longer than is necessary this reversal 15 in the direction of feed of the ribbon will take place practically instantaneously and therefore repeated impressions will be avoided at the ends of the ribbon. In order to prevent backward rotation of the ratchet wheels 52, 61, there is 20 provided a spring pressed non-return pawl 66 pivoted at 67 to the plate 28.

It is desirable that means be provided to prevent overthrowing of the ratchets 52, 61, owing to the fact that the spring 56 is likely to effect 25 a very quick return of the lever 50 assisted by the restoring of bell crank 26 which helps to make the action of the pawl 51 positive. For this purpose there is provided the stop 68 attached to the plate 28, the stop having a nose 30 projecting in front of the nose of pawl 51 so that said pawl will be jammed into the teeth in the ratchets 52, 61 thereby preventing overthrow of said ratchets due to their momentum.

The present invention provides a very simple 35 and effective mechanism for reversing the direction of feed of the inking ribbon and has the advantage that reversal of the ribbon takes effect without the use of any tension devices. Such devices, as was pointed out hereinbefore, tend 40 to cause dry spots in the ribbon due to repeated impressions through the same portions of the ribbon near the ends thereof owing to the fact that the ribbon usually becomes fully unwound from one of the spools and several impressions 45 are required to tension the ribbon sufficiently to operate the tensioning device to effect reversal of the direction of feed.

Another feature of the invention is that the mechanism automatically takes care of any mis- 50 adjustment of the parts when replacing the ribbon, as for instance would happen if the ribbon is replaced when the nose 59 is only half way between the portions of cam 60 which are designated 63, 64, respectively, in cam 60 since the 55 yielding manner of attachment of the ribbon 29 to the sleeves 30 permits the shafts 31 to turn idly without tearing the ribbon or breaking it.

It will, of course, be obvious that in such an event the type wheels would make repeated im- 60 pressions through the same area in the ribbon until the cam 60 had advanced far enough to re- 65 verse the ribbon and thereafter the ribbon would be fed properly. Should it happen that the ribbon has been improperly replaced so that repeated impressions occur through the same part 70 of the ribbon, as just described, the fact that suc- 75 ccessive impressions are weak or not clear in spite of the fact that a new ribbon has been installed should be a warning to the operator that the 76 parts are slightly out of time and it will be a simple matter to remove the upper half of the cabinet or housing and feed the ribbon by hand as by turning one or the other of the pinions 32 manually until the ribbon has been properly ad- 80 justed.

While there has been shown and described and pointed out the fundamental novel features of the invention as applied to a single modification, it will be understood that various omissions and substitutions and changes in the 80 form and details of the device illustrated and in its operation may be made by those skilled in the art without departing from the spirit of the invention. It is the intention therefore to be limited only as indicated by the scope of the 85 following claims.

I claim:

1. In combination, a ribbon driving shaft having a flat portion, a ribbon spool loosely mounted on said shaft and having a cut-away portion 90 adapted to face the flat portion, and means for securing the end of the ribbon to said spool comprising a member having lugs extending partially around the spool and over the ribbon to secure the latter to the spool, said clip having a portion thereof extending through the cut-away portion in the spool and in yielding contact with the flat portion of the shaft whereby to provide a yielding driving connection between the ribbon spool and the driving shaft. 95

2. In combination, a ribbon spool comprising a tubular member having a cut-away portion and adapted to be held in a loop formed in the end of the ribbon, said ribbon having a cut-away portion opposite the cut-away portion in the 105 spool, a shaft rotatably supporting the tubular member and having a flattened portion, and means for fastening the looped portion of the ribbon to the tubular member, said means including securing lugs extending around said 110 member and over the loop in the ribbon and a bent portion extending through the cut-away portions in the ribbon and tubular member into yielding contact with the flattened portions of the shaft whereby to provide a yielding driving 115 connection between the shaft and spool.

3. In combination, a ribbon storing member upon which the ribbon may be wound, a winding member therefor upon which the storing member is mounted for movement relative to the winding 120 member, and means for securing the ribbon to the storing member and having a yielding connection to the winding member whereby to permit said relative movement when movement of the ribbon in a winding direction is prevented. 125

4. In combination, a ribbon feeding member, a ribbon storing member freely mounted on the first named member and having an opening therein adjacent the first named member, and an element for securing one end of the ribbon to 130 the storing member, said element having a part thereof arranged to clamp the ribbon to the storing member and a part arranged to extend through the opening in the storing member and yieldingly connect the latter to the feeding mem- 135 ber for drive by the latter.

5. In combination, a driving element, a ribbon storing member mounted on the driving element and adapted to move relative to the latter, and an element for connecting the ribbon to said 140 storing member and having a portion thereof co-operating with the storing member to clamp the end of the ribbon to the storing member and having a portion adapted to yieldingly connect the storing member and driving element to resist 145 relative movement between the latter and the storing member and permit the driving element to effect winding of the ribbon on the storing member, said last named portion being adapted to yield to permit said relative movement when 150

excessive tension is applied to the ribbon by the driving element.

6. In combination, a ribbon feeding element, a ribbon spool loosely mounted on the feeding element, and a removable clip for securing the ribbon to the spool, said clip having spring fingers adapted to partially embrace the spool to clamp the ribbon to the spool and a portion adapted to bear against the ribbon feeding element to yieldingly connect the spool to the feeding element for drive by the latter, said portion permitting the feeding element and driving element to slip relative to each other when excessive tension is applied to the ribbon.
